(57) **CLAIM**

The ornamental design for a part of a filter, as shown and described.

DESCRIPTION

FIG. 1 is a top perspective view of a part of a filter;

FIG. 2 is a top plan view of the part of a filter shown in FIG. 1;

FIG. 3 is a bottom plan view thereof;

FIG. 4 is a front elevational view thereof;

FIG. 5 is a rear elevational view thereof;

FIG. 6 is a left side elevational view thereof; and,

FIG. 7 is a right side elevational view thereof.

The ornamental design which is claimed is shown in solid lines in the drawings. The broken lines depict portions of the part of a filter that form no part of the claimed design.
